UNITED STATES PATENT OFFICE.

EMANUEL HARMON, OF WASHINGTON, DISTRICT OF COLUMBIA.

POSTAGE AND REVENUE STAMP.

Specification forming part of Letters Patent No. 41,503, dated February 9, 1864.

To all whom it may concern:

Be it known that I, EMANUEL HARMON, of the city of Washington, and District of Columbia, have invented a new and useful Improvement in the Cancellation of Postage or Revenue Stamps; and I do hereby declare that the following is a full and exact description thereof, reference being had to the accompanying drawings.

My invention has for its object the preparation of a letter postage stamp or a revenue-stamp in such manner that when the canceling-mark ordinarily employed for canceling the same has once been impressed thereon such canceling-mark cannot be discharged from the face of the stamp without revealing the fact that the stamp has been subjected to such canceling-mark.

In the drawings, Figure 1 represents a United States postage-stamp.

Upon the face of the stamp, as represented in Fig. 1, by any suitable means I impress rectangular or waved web lines *a*, so that the entire area of the stamp shall exhibit a series of fine meshes, but of such a character as not to obliterate the denomination of the stamp, as represented in Figs. 2 and 3.

Fig. 4 represents one of the stamps having meshed lines *a* thereon, as shown in one of the preceding-named figures, together with the addition of a canceling-mark, *b*, impressed thereon, as ordinarily done by the act of canceling letter-stamps.

The ink employed with which to form the lines *a* is also employed to form the canceling-mark *b*, and thus when the stamp is once canceled, as represented in Fig. 4, it will be impossible to employ any chemical agent to remove the canceling-mark *b* without at the same time removing some portion of the meshed lines *a*, thus revealing the fact that the stamp has once been impressed with a canceling-mark. In this way it will be impossible to use a letter or revenue stamp a second time without detection.

I cover the face of the stamp with lines *a*,

as shown in the figures, so that if any portion of the canceling-mark is impressed upon the body of the stamp such mark will be certain also to be impressed upon said lines.

Instead of covering the face of the stamp with the lines *a*, as above described, such lines may be omitted altogether. In that case the canceling of the stamp should be made with the same ink or coloring-matter as that used in printing the stamp, or any essential part thereof, so that it shall be impossible to remove the cancellation without at the same time removing material portions of the stamp itself.

I am aware that for the purpose of preventing the alteration or falsification of written documents a mode has been adopted of printing a "design" in two colors upon paper, one of the designs being printed with indeleble ink, and the other with ink which can be washed out, and upon which printed colors the document is thereafter to be written; but this mode is objectionable, inasmuch as the writing-fluid thereafter employed to write upon the designs composed of printing-ink in different colors might be subject to removal by chemical agents without removing either one of the printed colors. This mode, therefore, I do not claim; but

What I claim as my invention, and desire to secure by Letters Patent of the United States, is—

1. The employment of the same ink to cancel a letter or revenue stamp which has been previously used to impress lines *a* upon the face of the stamp, substantially as and for the purpose described.

2. In canceling a letter or revenue stamp, the use of the same ink or coloring-matter as that employed in printing the same, or any essential part thereof, in the manner and for the purpose above described.

E. HARMON.
